(57) **CLAIM**

The ornamental design for a lounge chair, as shown and described.

DESCRIPTION

FIG. 1 is a front axonometric view of a lounge chair showing the new design;

FIG. 2 is a rear axonometric view thereof;

FIG. 3 is a side axonometric view thereof, the other side being a mirror image;

FIG. 4 is a bottom axonometric view thereof;

FIG. 5 is a front elevation view thereof;

FIG. 6 is a rear elevation view thereof;

FIG. 7 is a side elevation view thereof, the other side being a mirror image;

FIG. 8 is a bottom plan view thereof;

FIG. 9 is a top plan view thereof;

FIG. 10 is a front orthogonal view thereof;

FIG. 11 is a rear orthogonal view thereof;

FIG. 12 is a bottom orthogonal view thereof; and,

FIG. 13 is a rear and bottom orthogonal view thereof.

1 Claim, 13 Drawing Sheets(56)
